UNITED STATES PATENT OFFICE.

CHRIST O. ROSLAND, OF MANITOWOC, WISCONSIN.

FIRE-ESCAPE.

1,188,327.

Specification of Letters Patent. Patented June 20, 1916.

Application filed March 12, 1915. Serial No. 13,883.

To all whom it may concern:

Be it known that I, CHRIST O. ROSLAND, a citizen of the United States, residing at Manitowoc, in the county of Manitowoc and State of Wisconsin, have invented a new and useful Fire-Escape, of which the following is a specification.

This invention has reference to fire escapes and its object is to provide a fire escape structure whereby an occupant of a building may be quickly and safely lowered to the ground and the sustaining means for the escaped person will then return to the initial high position.

In accordance with the present invention there is provided a suitable casing which may be made practically weatherproof, and provision is made for raising the casing to and securing it at any suitable point on the exterior of a building from which it is desired an escape be made. The casing encloses automatically operating means including a receptacle large enough to hold one or more persons, which receptacle when subjected to the weight of a person desiring to escape will gravitate to the ground at a speed controlled by a suitable governor and further controlled at the will of an occupant of the receptacle. By the employment of mechanism always under tension the receptacle when relieved from the weight of the occupant returns to the high position, and is also capable of control from the ground, so that the receptacle may be stopped at intermediate points if such be desirable.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is an elevation of the casing and parts carried thereby with doors provided on the casing opened to expose interior parts, and some parts being in section and others broken away to expose more distant parts. Fig. 2 is a section on the line 2—2 of Fig. 1, with some

parts omitted. Fig. 3 is a section on the line 3—3 of Fig. 2. Fig. 4 is a section on the line 4—4 of Fig. 2. Fig. 5 is a plan view of the mechanism inclosed by the casing with some parts omitted and showing the casing in cross-section. Fig. 6 is a perspective view of controlling and latch mechanism employed in conjunction with other parts. Fig. 7 is a diametric section of a governor structure forming part of the invention. Fig. 8 is a section on the line 8—8 of Fig. 7. Figs. 9 and 10 are detail views of sustaining means for the casing.

Referring to the drawings there is shown a casing 1 which may comprise a box-like structure usually of metal, and this box-like structure is provided with a door 2 constituting one face portion of the casing, and a bottom 3 secured to the casing by hinges 4, so as to drop to a pendent position, but when lifted up constitutes a closure for the bottom of the casing. To hold the bottom 3 in place, the door 2 has a flange 5 at the bottom in position to underride the bottom member 3 when lifted. A hook 6 and catch 7 are shown as indicative of any suitable means for holding the door 2 in the closed position.

Within the casing 1 near the upper end thereof there is secured a face plate 8 located near what may be termed the back of the casing, that is, the portion of the casing remote from the door 2, and carried by the face plate 8 is another face plate 9 secured thereto and spaced therefrom by posts 10.

Mounted between the plates 8 and 9 is a spring drum 11 containing a spring 12 and mounted on a spring arbor 13, which latter carries a ratchet wheel 14, while the drum 11 carries a suitable pawl 15. Furthermore, the arbor 13 extends through the back of the casing and there has fast to it a crank 16 or other suitable means whereby the arbor 13 may be turned to wind the spring.

The spring drum 11 has a circular series of peripheral gear teeth 17 meshing with a gear pinion 18 on an arbor 19. A gear wheel 20 is carried by the arbor 19 and meshes with another pinion 21 on an arbor 22. The gear wheel 20 also meshes with a pinion 23 on an arbor 24 and the latter carries a ratchet wheel 25. The various arbors described are suitably journaled in the face plates 8 and 9. The arbor 22 is continued through the face plate 8 and ex-

rior thereto carries a gear wheel 26 upon which there is mounted a drum 27 having at the end remote from the gear wheel 26 a circumferential radial flange 28, and this drum is also provided on its periphery with a circular series of sprocket teeth 29. The gear wheel 26 is in mesh with a pinion 30 exterior to the face plate 9 and carried by an arbor 31, which in turn extends through the plate 9 and to the plate 8, and is journaled in both plates. The arbor 31 has a sleeve 32 thereon held to the arbor by a set screw 33, which under some circumstances may be loosened. Fast on the sleeve 32 near one end of the latter is a collar 34 from which project radially, and in opposite directions therefrom, pairs of ears 35. Each pair of ears carries a lever 36 having a ball or weight 37 at one end constituting the longer arm of the lever, and a friction member 38 at the other end of the lever and constituting the shorter arm thereof. In the path of each arm or friction member 38 is a friction block 39 made fast to the inner wall of the face plate 9 by rivets 40 or otherwise, and this block is centrally traversed by the arbor 31.

Secured to or formed on that end of the sleeve 32 remote from the collar 34 is a hub 41 carrying a disk 42. The hub 41 is interiorly hollow and applied to the arbor 31 within the hollow hub 41 is a ratchet 43 provided with a circular series of one way teeth 44. This ratchet 43 is secured to the arbor by a set screw 45 accessible through a passage 46 in the hub 41, and the latter is also entered by radial slots 47 on diametrically opposite sides, through which project free ends of springs 48 made fast to the other end of the sleeve 32 or to the collar 34, so that these springs engage the teeth 44 and will yield to a one-way rotation of the ratchet 43.

The disk 42 is surrounded by a brake band 49 having one end secured to a stud 50 fast to the plate 8 and the other end secured as by a pin 51 to one end of a lever 52 mounted on a pivot stud 43 secured to the plate 8. The lever 52 as shown is a lever of the first order and has a longer arm terminating in an angle extension 54 in accessible position, and this extension terminates in an eye 55. The lever 52 is under the normal control of a spring 56 tending to move that end of the lever connected to the brake band 49 in a direction to loosen the band and when the lever is moved in opposition to the spring 56, the band 49 is moved into frictional engagement with the periphery of the disk 42 to control or stop rotation thereof.

Journaled in and between the plates 8 and 9 is another arbor 57 shown separately in Fig. 6. This arbor carries an arm 58 which at the end remote from the arbor is

connected by a link 59 to the lever 52 on the same side of the pivot 53 as the angle extension 54. The arbor 57 which is a rock arbor, is also provided with an angle pin 60. Mounted on the arbor 57 to rock thereon is a pawl 61 having a nose 62 in position to engage the teeth of the ratchet wheel 25. The pawl 61 is provided with a toe 63 in the path of the pin 60. The pawl 61 is under the normal control of a spring 64 carried by the plate 9, so that under ordinary conditions the nose 62 of the pawl 61 is in the path of the teeth of the ratchet 25, but these teeth being one way teeth permit the rotation of the ratchet wheel 25 in one direction irrespective of the pawl 61. Rotation of the ratchet wheel in the other direction is, however, stopped by the nose 62 of the pawl 61 unless the pawl is lifted out of the path of the ratchet teeth, which latter condition exists when the lever 52 is moved sufficiently to cause the application of the brake band 49 to the brake disk 42.

Journaled at a high point in the casing 1, the plates 8 and 9 forming a convenient means for the purpose, is a winding drum 65 carrying a cord or rope 66. This rope passes through the eye 55 and is of sufficient length to reach the ground when unwound from the drum 65. Near the end of the rope 66 which is first applied to the drum 65 there is a knob or stop 67 so that when the rope is nearly or quite unwound from the drum 65 the knob 67 engages the extension 54 and so causes a rocking of the lever 52 against the action of the spring 56, such rocking being sufficient to apply the brake band 49 to the disk 42.

In order to facilitate the lowering of the rope or cord 66 when desired, it is provided at the end remote from the drum with a weight 68.

Applied to the drum 27 in engagement with the sprocket teeth 28 is a sprocket chain 69 connected at one end through a spring 70 to a bucket or receptacle 71 which is assumed to be of sufficient size to receive and sustain a human being and in some instances may be large enough to sustain several persons. The bucket or receptacle 71 is shown as provided with leg holes 72, so that the occupant may be conveniently seated in the bucket with the legs through the holes 72, whereby danger of falling from the bucket is minimized. That end of the chain 69 remote from the spring 70 is made fast to the bottom of the bucket, as shown at 73, and the chain is of sufficient length to reach from the drum 27 to the ground. At one side of the bucket or receptacle 71 is a hand grip 74 through which the rope or strand 66 is passed. By making this grip of two members engaging the strand 66 on opposite sides, the occupant of the bucket may easily squeeze the two members together to thus

apply friction to the rope or strand 66 and thereby exert a pull upon the lever 52 sufficient to cause the application of the brake band 49 with a force either wholly stopping the progress of the bucket or permitting it to fall slowly. Attached to the chain 69 near the spring 70 is an additional length of chain 75 terminating in a clip 76 designed to receive hose, so that the device may be utilized for raising fire hose, as well as providing for the escape of endangered occupants of the building.

At a suitable point upon the building there is provided a pulley 77 over which there is passed a rope or strand 78 having one end connected to an eye 79 on the upper end of the casing 1, while the rope may be of sufficient length to have the other end reach to the ground even when the casing is also at the ground. At appropriate points on the face of the building, say, at each floor, there is secured a catch member 79^a having a pin 80 rising therefrom, and at other appropriate points in spaced relation to the catch member 79^a is another catch member 81. At correspondingly spaced points the casing 1 has an eye 82 and a stud 83 projecting therefrom in position to be engaged by catch member 79^a and 81, respectively.

When the casing is lifted to an appropriate height so that the eye 82 and stud 83 are above the respective catch members, the casing may then be lowered, so that the eye 82 is traversed by the pin 80 and the catch member 81, which is provided with a slot 84, is engaged by the stud 83, which latter enters the slot 84.

The casing 1 may be assumed to have been drawn up on the building to the appropriate height at any time, or when needed. Ordinarily the bucket or receptacle 71 is in the raised position, and may then be housed within the casing 1 when the latter is of sufficient size. The bucket is constrained to assume and remain in the elevated position because of the spring 12 which is of proper size and power for the purpose.

In case of a fire, the endangered occupant of the building opens the door 1 by manipulating the latch 6, whereupon the bottom 3 drops by gravity to the open position and the receptacle or bucket 71 may likewise drop and at any rate is then in position to be readily reached by the endangered person. On stepping into the bucket the weight of the occupant will at once tend to lower the bucket, since such weight is in excess of the lifting power of the spring 12.

The bucket 71 is ordinarily locked against lowering by the engagement of the pawl 61 with the ratchet wheel 25, so that the occupant must grasp the rope 66, thus moving the lever 52 in a manner to carry the nose 62 out of the path of the teeth of the ratchet 25, but this movement need not be sufficient to

apply the brake band 49. Now the bucket continues to fall under the weight of the occupant, but the fall is modified by the action of the governor, and this action may be further controlled by grasping the grip 70 member 74 and thereby applying a force to the rope or cord 66, which will hold the brake band 49 in the desired frictional engagement with the brake wheel or disk 42. If the brake band be applied with sufficient force the falling progress of the bucket 71 may be entirely stopped.

When the occupant of the bucket reaches the ground the rope 66 may be released, whereupon the brake is disengaged, although the pawl 61 is reapplied. Now, however, the reaction of the spring 12, exerting a force sufficient to lift the bucket, causes a rising of the bucket by reversing the direction of movement of the drum 27. This movement is not interfered with by the ratchet wheel 25 since the teeth of the ratchet wheel are so related to the nose 62 of the pawl 61 as to move freely therewith. However, the governor will still control the movement sufficiently to prevent the bucket from rising too rapidly.

The governor may be thrown out of commission, especially as to rising movements of the bucket by loosening or removing the set screw 33, whereupon the arbor 31 will rotate without carrying the sleeve 32 with it. However, this free rotation is in but one direction, since the springs 48 engage the ratchet teeth 44 and so the governor is moved in the corresponding direction. However, when the arbor 31 is rotated in the other direction the springs 48 merely ride over the teeth 44 without rotating the governor. By this means the bucket may be lowered under the control of the governor, or may be raised more rapidly because the governor is then inactive. Too rapid movement, however, or a stopping of the bucket at any desired point is readily controlled by the brake, which may be manipulated at will by pulling the cord 66.

While the device has been described as a fire escape and is primarily designed for such purpose, it is capable of use for many purposes, such as the lifting or lowering of goods and the like, and consequently the device in so far as applicable to various uses is not confined strictly to use as a fire escape.

The structure is capable of manufacture in sufficiently small size to be ordinarily stored in a room from which, in the event of a fire, escape may be made. The stored fire escape device can then be readily lifted to the exterior of the building and placed upon the supports 79^a and 81, or other suitable supports, whereupon the doors may then be opened and the apparatus is ready for use in the manner already described.

4
What is claimed is:—

1. A fire escape or the like, comprising a receptacle, suspending means for the receptacle having a constant tendency to elevate the latter, a governor for controlling movements of the suspending means and active to control the movements of the receptacle in either the up or down direction, said governor having means for converting it into a one-way governor, and readily controllable means for locking the receptacle against movements in opposition to the elevating tendency of the suspending means.
- 15 2. A fire escape or the like, comprising a receptacle, suspending means for the receptacle having a constant tendency to elevate the latter, a governor for controlling movements of the suspending means during either the rise or fall of the receptacle, a brake drum constantly connected to the governor and having means for connecting both the brake drum and the governor to or loosening them from the suspending means, manually operable means for controlling the brake drum, and means for connecting the governor to the parts controlled thereby for one-way actuation of the governor.
- 30 3. A fire escape or the like, comprising a receptacle, suspending means for the receptacle having a constant tendency to elevate the latter, a centrifugal governor and a brake drum having common connections for controlling the suspending means, positive means for locking the receptacle against movements in opposition to the elevating tendency of the suspending means, means for converting the governor into a one-way governor for controlling the lowering movements only of the receptacle, controlling means for the brake drum, and manually operable means common to the locking means and the controlling means for the brake drum.
- 45 4. A fire escape or the like comprising a receptacle, a spring drum and train of gearing connected thereto, a sprocket connected to and driven by the gearing, an effectively endless chain carried by the sprocket and in turn carrying the receptacle, a governor controlling the movements of the receptacle in either direction, stop means for holding the receptacle against movements in opposition to the spring, a brake for controlling or stopping the movements of the receptacle in either direction, and operating means for the stop means and for the brake for controlling either in alternation with the other.
- 50 5. A fire escape or the like comprising a receptacle, a spring drum and train of gearing connected thereto, a sprocket connected to and driven by the gearing, an effectively endless chain carried by the sprocket and carrying the receptacle, a gov-

ernor connected to and driven by the gearing for controlling movements of the receptacle in either direction, a ratchet wheel connected to and driven by the gear train, a pawl for the ratchet wheel and related thereto to arrest movement of the gear train in opposition to the action of the spring, a brake for controlling or stopping movements of the receptacle in either direction, and operating means for the brake and for the pawl for moving one at a time in alternation with the other.

6. A fire escape or the like comprising a train of gearing and a spring connected thereto for actuating the gearing, a sprocket connected to the train of gearing for actuation thereby, an effectively endless sprocket chain carried and controlled by the sprocket, a receptacle carried by the chain, a governor connected to the gearing, a brake member also connected to the gearing, a ratchet wheel connected to the gearing, a pawl for controlling the ratchet wheel, a spring-actuated lever including means for controlling the pawl, a brake band carried by the spring-actuated lever in operative relation to the brake member, and means for operating the lever and through the latter operating the brake and pawl in opposition.

7. A fire escape or the like comprising a train of gearing and a spring connected thereto for actuating the gearing, a sprocket connected to the train of gearing for actuation thereby, an effectively endless sprocket chain carried and controlled by the sprocket, a receptacle carried by the chain, a governor connected to the gearing, a brake member also connected to the gearing, a ratchet wheel connected to the gearing, a pawl for controlling the ratchet wheel, a spring-actuated lever including means for controlling the pawl, a brake band carried by the spring-actuated lever in operative relation to the brake member, and means for operating the lever and through the latter operating the brake and pawl in opposition, said lever operating means comprising a flexible rope or cord and a winding drum therefor.

8. A fire escape or the like comprising a train of gearing and a spring connected thereto for actuating the gearing, a sprocket connected to the train of gearing for actuation thereby, an effectively endless sprocket chain carried and controlled by the sprocket, a receptacle carried by the chain, a governor connected to the gearing, a brake member also connected to the gearing, a ratchet wheel connected to the gearing, a pawl for controlling the ratchet wheel, a spring-actuated lever including means for controlling the pawl, a brake band carried by the spring-actuated lever in operative relation to the brake member, and means for operating the lever and through the latter operating

ing the brake and pawl in opposition, said lever operating means comprising a flexible rope or cord and a winding drum therefor, and the receptacle being provided with a 5 grip member through which the cord is passed.

9. A fire escape or the like comprising a receptacle, power storing means, elevating means for the receptacle under the control 10 of the power storing means and responsive to a superior weight placed in the receptacle to permit the latter to fall, and a brake means for the receptacle and power storing means comprising a brake disk and brake 15 band, a shaft controlled by the receptacle, a ratchet on and provided with means for securing the ratchet to and loosening it from the shaft, and elastic members connected to the brake disk in position to engage 20 the ratchet for riding freely over the ratchet in one direction of rotation of the shaft when the ratchet is secured to said shaft.

10. A fire escape or the like comprising a 25 receptacle, power storing means, elevating means for the receptacle under the control of power storing means and responsive to a superior weight placed in the receptacle to permit the latter to fall, and a brake means 30 for the receptacle and power storing means comprising a brake disk and brake band, a shaft controlled by the receptacle, a ratchet on the shaft, and elastic members connected to the brake disk in position to engage the

ratchet for riding freely over the ratchet in 35 one direction of rotation of the shaft, said brake disk being also provided with means for fixedly securing it to the shaft.

11. A fire escape or the like comprising a spring-actuated gearing with means for 40 storing power in the spring, a receptacle, means for sustaining the receptacle with said sustaining means connected to the gearing for the elevation of the receptacle by the power of the spring, and a brake and 45 governor structure connected to the gearing, the governor comprising a centrifugal 50 governor for regulating the speed of the movement of the receptacle, and the brake comprising a brake disk with a brake band in 55 operative relation thereto, a shaft traversing the brake disk and connected to the gearing, a sleeve on the shaft having one member of the governor fast thereto for rotation by the sleeve, a ratchet carried by 60 the sleeve, and yieldable members carried by the sleeve in operative relation to the ratchet and in turn connected to the brake disk, said sleeve having means for securing it to or releasing it from the shaft.

In testimony that I claim the foregoing as my own, I have hereto affixed my signature in the presence of two witnesses.

CHRIST O. ROSLAND.
